SAFETY APPARATUS

Lieutenant Hobson Loyd, Curtissville, Pa., assignor of one-half to Nichola C. Petcoff, Curtissville, Pa.

Application September 13, 1935, Serial No. 40,498

5 Claims. (Cl. 114—44)

This invention relates to a safety apparatus for marine vessels and has for its object to provide, in a manner as hereinafter set forth, an apparatus of the class referred to for raising a sunken vessel to the water level.

A further object of the invention is to provide, in a manner as hereinafter set forth, an apparatus of the class referred to for expeditiously raising a vessel, in which the apparatus is installed as a permanent part thereof, from a sunken position to the water level.

A further object of the invention is to provide, in a manner as hereinafter set forth, an apparatus of the class referred to including means for indicating the approximate point where a vessel sinks, as well as acting as an air intake for a compressor on the vessel, and with the compressor functioning for supplying air to receivers carried by the vessel to provide buoyant lifting elements or pontoons acting to raise the vessel from its submerged position.

Further objects of the invention are to provide, in a manner as hereinafter set forth, an apparatus for the purpose referred to which is strong, durable, readily installed with respect to a vessel to form a permanent part of the latter, conveniently thrown into operation for the purpose of raising the vessel when submerged and thoroughly efficient in its use.

With the foregoing and other objects in view the invention consists of the novel construction, combination and arrangement of parts as will be hereinafter more specifically described and illustrated in the accompanying drawings wherein is shown an embodiment of the invention, but it is to be understood that changes, variations and modifications may be resorted to which fall within the scope of the invention as claimed.

In the drawings:

Figure 1 is a side elevation of a vessel, broken away, showing the installation therewith of the safety apparatus in accordance with this invention.

Figure 2 is a longitudinal sectional view illustrating the form of the lifting elements or pontoons employed. The element is shown in active position and its relation to one of the sides of the vessel.

Figure 3 is a fragmentary view in side elevation of the inner section of the lifting elements or pontoons.

Figure 4 is a side elevation of the outer section of the lifting elements or pontoons.

Figure 5 is a vertical sectional view of the buoyant combined signalling and air intake element

and the housing for the latter. The signalling and air intake element is illustrated as being projected from the vessel, and

Figure 6 is a section on line 6—6, Figure 5.

Referring to the drawings, 7 generally indicates the simulation of a vessel which is submerged in a body of water. The water level is designated 8. The sides of vessel 7 are indicated at 9, 10. The upper and lower decks of the vessel are designated 11, 12 respectively.

Supported from the deck 12 is an air compressor 13, a winding drum 14 and a compressed air storage tank 14a. Leading from the compressor 13 to one end of the tank 14a is a compressed air supply line 15. Extending from the other end of tank 14a is a compressed air discharge line 16 provided with a cutoff 16a. Communicating with compressor 13 is an air feed line 17 in the form of a rubber hose of the desired length which is normally wound on drum 14. The compressor may be operated from an electric motor, not shown. The vessel may be provided with a storage battery, not shown, connected with the motor and it may also be supplied with a generator, not shown, connected with the battery.

Each side of the vessel, at the desired distance above the deck 12, is formed with a series of spaced parallel openings transversely thereof and of circular cross section. The number of openings of each series may be as desired. With reference to Figure 2, one of said openings is illustrated and indicated at 18. The opening 18 is shown, by way of example, in the side 10. The outer end of the wall of opening 18 is rabbed, as at 19, to form an annular seat 20 and an annular enclosing wall 21 for seat 20. The vessel side 10 is shown as being formed with an upper and a lower socket 22, 23 respectively arranged in parallelism and opening at the inner face of such side 10. The sockets 22, 23 are arranged in proximity to the opening 18. The bases of the sockets are designated 24. Leading from the bases of the sockets and opening into the rabbet 19 are guide channels 25, 26 of less diameter than that of the sockets 22, 23. There will be associated with each of the openings in each of the sides 9, 10 of the vessel 7 a pair of sockets and a pair of guide channels of the arrangement such as shown in Figure 2.

There is associated with each opening 18 a sectional lifting element or pontoon indicated generally at 27. The elements 27 are of like construction and each consists of a stationary outer section 28 and a spring controlled oppositely slideable inner section 29 which is arranged concentrically to section 28. The latter consists of a cylindrical

body portion 30 open at each end and formed at its inner end 31 with an outwardly directed annular flange 32. The outer end 33 of body portion 30 is provided with an inwardly extending annular flange 34 formed with an annular groove 35 which opens into the body portion 30. The flange 32 is formed with a pair of spaced parallel apertured lugs 36. Mounted against the inner end edge of body portion 30 and the flange 32 is a sealing gasket 37. The inner end 31 of body portion 30 is closed by a head member 38 of dome-shape cross section and which is formed with an annular flange 39 seating against gasket 37. The flange 39 is formed with a notch 40 which opposes the space between the lugs 36 when member 38 is arranged to close the inner end of body portion 30. The flange 39 is hinged to flange 32, as at 41. Pivotally connected to the lugs 36, as at 42, is a clamping bolt 43 which associates with a clamping nut 44 for tightly binding flange 39 against gasket 37 and for tightly binding the latter against flange 32 to form an air tight seal when member 38 closes the inner end of body portion 30. Anchored to and opening into the member 38 is a compressed air intake pipe 45 provided with a gauge 46. The member 38 carries an outwardly directed annular boss 47 which encompasses pipe 45 and has connected thereto a sealing medium 48 which surrounds pipe 45. The member 38 has an opening 49 which registers with the boss 47 and receives the discharge end of pipe 45. Extending from the inner face of member 38, adjacent opening 49, is a coupling eye 50. Mounted in the groove 35 and extending beyond the free edge of flange 34 is a resilient sealing gasket 51. The section 28 is fixedly secured to and extends inwardly from the inner end of the wall of opening 18.

The section 29 consists of a cylindrical body portion 52 open at its inner end and closed at its outer end by an integral circular head 53 of greater diameter than that of body portion 52. The head 53 is of greater thickness than the body of the portion 52, is of dome-shape contour in cross section and is oppositely disposed relative to head member 38. The head 53 is disposed concentrically to body portion 52 and is formed with a pair of diametrically disposed oppositely extending apertured lugs 54, 55. The inner end of body portion 52 is formed with an outwardly extending annular flange 56 formed with an annular groove 57 which opens at the outer edge of the flange. The diameter of body portion 52 is materially less than that of body portion 30 of section 28. Formed integral with the inner face of body portion 52 between its vertical median and inner end is a spider 58 carrying centrally thereof a coupling eye 59. Anchored to the eyes 50, 59 are the ends 60 of a coiled controlling spring 60 for section 29. Mounted in and extended from the groove 57 is a resilient water sealing gasket 61. The gasket 61 encompasses and permanently bears against the outer periphery of body portion 52. The gasket 61 permanently bears against the inner face of body portion 30. The latter has its outer end flush with the seat 20. Anchored at their outer ends to the lugs 54, 55 are the combined guide and stop elements 62, 63 respectively operating in the channels 25, 26 respectively and in the sockets 22, 23 respectively. Each of the elements 62, 63 consists of a rod 64 provided on its inner end with a piston head 65 formed with a packing 66 riding against the wall of a socket to provide a water tight seal.

The piston heads 65 coact with the bases 24 of the sockets for limiting the outward shift of the rods 64 and section 29.

Normally, the section 29 is drawn into section 28 by spring 60, and when so positioned the head 53 is arranged against seat 20 and encompassed by wall 21. The normal position of elements 62, 63 is within a pair of sockets and a pair of guide channels and with the piston heads 65 thereof at the mouths of the sockets. On the application of compressed air to an element 21 the section 29 is extended outwardly with respect to section 28 and against the action of spring 60. The sections 28, 29 are completely filled with compressed air which provides the element 21 with a lifting function.

The discharge line 16 opens into a supply line 67 which is common to the intake pipes 45 of the elements 27 whereby they are substantially simultaneously completely filled with compressed air so that they will possess a lifting function to raise the sunken vessel to the water level. Preferably, the tank 14a will contain a body of compressed air sufficient for completely filling the elements 21, however, the tank 14a, when opened for discharge therefrom, is supplied with compressed air from the compressor, as the latter will be thrown into operation at this time. The feed for the compressor is had through the line 17.

The apparatus includes a buoyant, projectable, combined signalling and air intake element 68 of which the line 17 forms a part. The element 68 is normally housed within and projectable from the vessel. The element 68 includes a cylinder 69 open at its top and having its bottom 70 formed with an axial opening 71 and a depending collar 72 registering with the wall of opening 71. The top of cylinder 69 is provided with a laterally extending annular flange 73. Detachably secured to flange 73 is a closure 74 formed with a depending closed bottom tubular member 75 which provides a socket 76. The upper end of member 75 registers with an opening 76a. A vertical tubular extension 77 registers with opening 76a. The latter and extension 77 forms a continuation of socket 76. The upper end of extension 77 is normally closed by a hinged cap 78. The closure 74 is provided axially thereof with an opening 79 having a beveled wall which constitutes a valve seat. Depending from closure 74 is a coupling sleeve 80 of greater diameter than and surrounding opening 79. Secured upon closure 74 are signals 81 in the form of electric lamps. Arranged between the lamps 81 is a hollow, spherical guide 82 having its body formed with apertures 83 and a passage 84 which aligns with one of the apertures 83. The guide 82 is provided with a depending collar 85 which is integral with closure 74 and registers with opening 79. Integral with the top of guide 82 is a cage 86 for a float 87 on the upper end of a valve stem 88. The latter extends through the guide 82 and opening 79 into sleeve 80 and carries on its lower end a valve 89 which coacts with the seat formed by the wall of opening 79 to close the latter for a purpose to be referred to. Supported in a bracket 90 within the cylinder 69 is a normally de-energized magnet 91 which, when energized, withdraws a bolt 92 from locking position. The bolt 92 normally acts to hold an expelling spring 93 in contracted position. The spring 93 is arranged in socket 76 and functions, when released, to partly project an extendible antenna 95 from the upper end of the

extension 77. The bolt 92 is slidably mounted in an opening 96 formed in the body of the member 75 and is arranged to oppose the armature of magnet 91 and normally extends diametrical-
 ly of socket 76 to hold the spring 93 contracted. The cap 78 closes extension 77 to prevent entrance of water to the latter and includes an inclined arm 78^a arranged, when the cap is closed in the path of a shifter 79^a carried by a float 10 controlled vertically movable rod 80^a operating through closure 78 and a vertical guide tube 81^a. When the element 68 is projected upwardly, the float 82^a on rod 80^a holds the rod 80^a in an elevated position with the shifter 79^a above the arm 78^a. The armature of the magnet 91 is extended, as at 91^a and arranged below the lower end of rod 80^a. When magnet 91 is energized the rod 80^a is attracted to the extended portion 91^a of the armature whereby a rod 80^a is lowered moving the shifter 79^a in a direction to engage arm 78^a and shift the cap 78 to open position, as shown in full lines, Figure 5. Circuit connections for the magnet 91 are indicated at 97. Circuit connections for the lamp are designated 98.
 15 The line 17 is normally wound on drum 14 and winds therefrom when the element 68 is projected. The line extends through opening 10 in the bottom of cylinder 69 and has its upper end connected to and opens into sleeve 80.
 20 The apparatus includes a combined housing and projecting element 99 for the element 68. The element 99 comprises vertical cylinder 100 having its bottom formed with an axial opening 101 and a depending collar 102 surrounding the latter. The cylinder 100 is open at its upper end. The deck 8 is formed with an opening 103 to the wall of which is anchored the upper end of cylinder 100. A spring controlled cover 104, hinged to deck 8, is provided for normally closing the upper end of the cylinder 100. The cover is hinged to deck 8, as at 105, and has an upstanding lip 106 engageable by a pivoted latch 106^a for releasably retaining the cover 104 in position to close the upper end of cylinder 100.
 25 The latch 106^a is pivoted, as at 107, to deck 8 and carries a depending operating handle 108 which passes through an opening 109 in deck 8. Suitable resilient sealing means is arranged in opening 109 and through which passes handle 108. Pivottally connected to the cover 104, as at 110, is a spring controlled pull member 111 for quickly pulling cover 104 open when the latch 106^a is moved to release the cover. The member 111 includes a curved outer part 112 and a straight inner part 113. The member 111 passes through an opening 114 formed in deck 8. Suitable resilient sealing means is arranged in opening 114 and through which passes the member 111. Anchored at its lower end, as at 116 with
 30 the vessel is a controlling spring 117 for member 111. The lower end of part 113 of member 111 is connected to the upper end of spring 117, as at 118. The cover 104 is shifted to closing position relative to cylinder 100 and latched in such position against the action of spring 117. Arranged within the cylinder 100 is a set of spaced parallel expelling springs 119 for the element 68. The springs 119 are anchored at their lower ends, as at 120, to the upper face of the bottom of cylinder 100. The upper ends of springs 119 are anchored, as at 121, to the lower face of a follower plate 122 formed with an axial opening 123. The line 17 passes through the opening 101 in the bottom of cylinder 100 and the opening 123

in the follower plate 122. The normal position of element 68 is housed within cylinder 100 against the action of the springs 119. When the element 68 is housed in cylinder 100 it bears on the upper face of follower plate 122 and is releasably confined in such position, against the action of springs 119, by the cover 104 when the latter is latched. When element 68 is projected or expelled from cylinder 100 the line 17 winds off drum 14.

Connected to the collars 72, 102 and encompassing the line 17 are packing means 124, 125 respectively to provide a water tight joint. Interposed between flange 73 and closure 74 is a sealing gasket 126.

The circuit connections 98 extend through line 17 to compressor 13 and from the latter to a source of electrical energy such as a battery or generator.

The flanges 34, 56 coact to provide a lock joint 20 for the sections of a lifting element. The longer the section 29 of a lifting element, the longer the lock joint will be for the purpose of sustaining section 29 when projected relative to section 28.

When element 68 is projected from element 99 25 the float will provide for the seating of valve 89 whereby line 17 will be shut off to the entrance of water. When element 68 extends above the water level, the valve 89 will automatically open to permit line 17 to feed air to the compressor. 30 At this point the circuit for the lamps will be closed whereby the signals will be made active, magnet 81 energized and the bolt 92 shifted to release the spring 93 to provide for the projecting of the antenna to above the lamps. In the meantime, the line 16 will have been opened and the compressed air supplied to the lifting elements. If the compressed air from the tank is not sufficient to completely fill the lifting elements to project the sections 29 of these latter, 40 the compressor will be thrown into operation to supply the necessary additional compressed air. When the sections 29 of the lifting elements have been extended to their outermost position, the lifting elements will then act to raise the submerged or sunken vessel to the water level. 45

What I claim is:

1. In a safety apparatus for a marine vessel, the combination with the hull of the vessel provided transversely of each side thereof with a 50 series of inwardly opening sockets, outwardly opening channels leading from and of reduced diameter relative to the bases of the sockets and openings disposed in juxtaposition to the sockets and channels, of an extendible compressed air receiving lifting element mounted in each opening and disposed inwardly and outwardly relative thereto, said element formed of a fixed closed inner end annular outer section and a closed outer end extendible inner section arranged concentrically to the outer section, said inner sections having their outer ends provided with laterally extending means for closing the outer ends of the outer sections and the outer ends of said openings and channels when the inner sections 55 are in non-extended position, said outer sections being provided with compressed air intakes at their inner ends, a controlling spring for the inner section arranged within and anchored to the outer and inner sections, piston rods providing 60 guides slidably mounted in said sockets and channels and connected at their outer ends to the lateral means on the inner sections, and pistons constituting stops mounted in said sockets and connected to the inner ends of said rods. 65
 70
 75

2. The invention as set forth in claim 1 having respectively the controlling springs for the extendible inner sections of said elements disposed axially of the latter, the inner sections of said elements provided therein and intermediate their ends with fixed spiders, the inner ends of the controlling springs anchored to the inner ends of the fixed sections of said elements, and the outer ends of the controlling springs anchored to said spiders.
3. The invention as set forth in claim 1 having the outer end of the inner face of the fixed outer section and the inner end of the outer face of the inner extendible section of each element formed with coacting parts to provide a lock joint for the sections when extended.
4. In a safety apparatus for a marine vessel, spaced compressed air receiving sectional lifting elements of pontoon-like form, adapted to be mounted in and including spring controlled sections for extending from the sides of the vessel on the application of compressed air to said elements, each of said elements provided with a compressed air intake at its inner end and a lock joint for its sections when the inner sections are extended, an air compressor, a controllable compressed air supply means leading from the compressor and common to said intakes, a winding drum, a normally confined spring controlled projectable buoyant air feed structure for projection from the vessel and including an elongated flexible valve controlled air supply conducting line extended
- from the inner end of said structure, said line being wound intermediate its ends on said drum and having its inner end permanently communicating with the compressor, and means for releasing said structure from its confined position to provide for the automatic projecting of said structure to a position to float at water level for supplying air to the compressor, said line winding off said drum on the release of said structure.
5. In a safety apparatus for a marine vessel, a compressed air receiving lifting element of pontoon-like form adapted to be mounted in the side of the vessel and formed of a fixed annular outer section having a closed inner end and an extendible inner section arranged concentrically to the outer section and having a closed outer end, the outer end of the inner face of the outer section and the inner end of the outer face of the inner section having coacting means to provide a lock joint for said sections when the inner section is extended, each of said means including a resilient annulus abutting one of said sections, a controlling spring for said inner section arranged within said sections, said inner section provided therein intermediate the ends thereof with a spider, said spring having its inner end anchored to the closed inner end of the outer section and its outer end anchored to said spider, and said outer section having its inner end provided with a compressed air intake.

LIEUTENANT HOBSON LOYD.
